UNITED STATES PATENT OFFICE.

FREDERICK M. WHYTE, OF TARRYTOWN, NEW YORK.

CAR-END CONSTRUCTION.

1,384,368.

Specification of Letters Patent. Patented July 12, 1921.

Application filed October 8, 1919. Serial No. 329,226.

To all whom it may concern:

Be it known that I, FREDERICK M. WHYTE, a citizen of the United States of America, residing at Tarrytown, in the county of 5 Westchester and State of New York, have invented certain new and useful Improvements in Car-End Constructions, of which the following is a specification, reference being had therein to the accompanying 10 drawings.

The invention relates to car body constructions of that type employing metal plates, and it is the object of the invention to secure with a minimum weight of metal 15 the maximum strength and durability, and also a construction which is easily manufactured and forms a thorough weatherproof covering.

In the present state of the art various constructions have been devised in which metal plates have been bent, pressed or otherwise fashioned and secured to each other to form the constituent elements of a truss; but in 20 all of these prior structures there have been certain defects which it is the object of the 25 present invention to overcome. For instance, where the plates are bent to form corrugations there is difficulty in forming a satisfactory weatherproof joint at the ends 30 of such corrugations. Also where the corrugations are of a rounded cross-section the metal is not so disposed as to be highly efficient in forming a truss. Where ribs or 35 panels terminating inside the margin of the sheet are pressed therein, this requires relatively soft metal to successfully produce the 40 required depth of rib, and by drawing or stretching certain portions of the section reduces the strength; also the cost of manufacture is increased. Where the structure is 45 built up from a plurality of sheets of thin gage metal the amount of surface exposed to corrosion is greatly increased, while a thinner gage of metal decreases the length of life.

To overcome these defects some of the features of my invention are: first, a single ply metallic plate construction in which the metal is advantageously located to produce 50 the maximum trussing effect; second, a fashioned metal plate, which may be developed from a metallic sheet without material drawing or flowing of the metal; third, a metallic plate, which is cold fashioned, and therefore 55 can be manufactured at small cost in com-

parison with hot pressed plates; fourth, a plate having the greater portion of its area disposed in two separated and substantially parallel planes with connecting portions for carrying the stresses from one plane to the other; fifth, a plate having its major portion in the two planes, as just described, with another portion bent into a plane transverse to the first-mentioned planes to form a corner construction; sixth, a construction 60 which can be formed from a rectangular blank and maintains its rectangularity when fashioned so as to require no trimming; seventh, a plate having a ribbed corner, or angle bend, formed without material drawing 65 or stretching of the metal.

In the drawings I have shown my invention as applied to a construction of metallic plate for car ends, but it is obvious that the essential features of the construction are applicable to other structures.

Figure 1 is an end elevation of the car showing my improved construction;

Fig. 2 is a side elevation thereof;

Fig. 3 is a vertical longitudinal section;

Fig. 4 is a perspective view of a portion of one of the plates;

Fig. 5 is a horizontal section thereof.

The metallic blanks from which my improved construction is formed are preferably 85 rectangular and extend transversely of the end of the car, being of sufficient length to turn corners and overlap the sides of the corner posts. The metal in the body of the plate is mainly distributed in two planes 90 parallel to and separated from each other, while the continuity is maintained by zig-zagging from one plane to the other. This will form a series of panels alternately in the different planes, the width of said panels 95 and the angle of the transversely extending connecting portions being selected to place the maximum amount of metal in work at points farthest removed from the neutral axis. Specifically, the width of the panel is 100 preferably from four to six times the depth of distance between the two planes and the angle of the transverse portions is preferably approximately 60° to the parallel planes.

With the plate as thus far described, it would be difficult to form a weatherproof joint at the ends thereof, nor would it be possible to turn a corner without distortion, because of the greater length of profile in 110

the outer plane over that in the inner plane. I have, however, devised a construction in which the ends of the plate may be bent at right angles without drawing or distorting 5 the metal but merely bending the same. The principle underlying the construction is illustrated in Fig. 4 in which A and B are alternate panels connected by the inclined portions C, and D is a portion of the plate 10 at the end thereof extending transversely to the planes of the portions A and B and preferably at right angles thereto. In forming the paneled portion one dimension of the original blank will be materially 15 shortened and to compensate for this in the transverse portion D without any drawing or stretching of the metal, there is provided one or more ribs E. To avoid drawing or stretching of the metal in the longitudinal 20 plane thereof, the corners are so fashioned that all horizontal sections are of substantially equal length from one end of the plate to the other. Thus as shown, the panels B are connected with the portion D by the 25 obliquely inclined portion B' and a flat portion B² which has an angle-bend therein. The inner panels A are connected with the portion D by a rounded bead A' and the ribs E are arranged opposite the obliquely 30 inclined portions C. This will make the profile length of the various horizontal cross-sections of the blank equal and the connecting portions of the metal are also fashioned in such a manner that all vertical 35 cross-sections are of the same length of profile. Consequently, the blank may be pressed without any material drawing or stretching of the metal and the marginal portions of the blank will maintain their 40 original angular relation, although the over-all dimensions are shortened.

The plates, as above described, can be readily cold pressed and when applied to a car-end will extend horizontally from corner to corner thereof, the flange portions D overlapping the corner posts. To complete a weatherproof joint it is only necessary to close the ends of the ribs E which may be accomplished by inserts I welded 50 or otherwise secured. The plate is bolted or otherwise secured to the corner posts and wooden strips J may be placed in the spaces formed between the outer and inner panels to which the lining K of the car may be 55 attached. Where the plates are used for the sides of the car or in other locations, they may be modified as necessary, but the same principle of construction is maintained by fashioning and trussing without materially 60 drawing the metal.

To facilitate the pressing of the sheet and the equalizing of the profile lengths, the inclined portions C are preferably connected to the panels A and B by slighter inclines C' and C².

What I claim as my invention is:

1. A formed metal sheet having portions thereof lying in spaced parallel planes and an end portion lying in a third plane transverse to said parallel planes, the portions 70 in said several planes being connected by fashioned portions maintaining a substantially uniform length of section in all parallel intersecting planes.

2. A fashioned metal plate of a form 75 which can be developed from a plane sheet without material drawing or stretching of the metal, said plate having portions lying in spaced parallel planes, and an end portion lying in a plane transverse to said parallel planes.

3. A fashioned metal plate developed 80 from a plane sheet without material drawing or stretching of the metal, said plate having portions lying in spaced parallel planes, an end portion lying in a transverse plane, and ribbed corners connecting the portions in the several planes.

4. A fashioned metal plate having the greater part of its area disposed in spaced 90 parallel planes with transverse connecting portions therebetween, and a portion at the end thereof, in a plane transverse to all of said planes, said portions in the several planes being connected by compensating 95 portions maintaining substantially equal lengths of cross section.

5. A fashioned metal plate of a form which can be developed from a plane sheet without material drawing or stretching of 100 the metal, the body of said plate having successive portions arranged in spaced parallel planes with intermediate obliquely inclined connecting portions, and a portion at the end of said parallel and obliquely inclined portions in a plane transverse thereto.

6. A fashioned metal plate of a form which can be developed from a plane sheet without material drawing or stretching of the metal, said plate having a body with 110 successive portions lying in spaced parallel planes and intermediate obliquely inclined connecting portions, a portion at the end of said parallel and obliquely inclined portions in a plane transverse thereto, and compensating portions fashioned to maintain 115 equal lengths of profile in all portions of the sheet.

7. A fashioned metal plate of a form which can be developed from a plane sheet 120 without material drawing or stretching of the metal, the body of said plate having successive portions lying in spaced parallel planes with intermediate obliquely inclined connecting portions, a flanged portion at 125 the end of said parallel and obliquely inclined portions in a plane transverse thereto, and a rib extending around the corner of said flange reinforcing the same and forming a compensating means for maintaining 130

equal lengths of profile in the plate in all parallel intersecting planes longitudinally and transversely thereof.

8. A fashioned metal plate for car ends of
 5 a form which can be developed from a plane sheet without material drawing or stretching of the metal, the body of said plate having the greater part of its area lying in two parallel spaced planes with intermediate
 10 obliquely inclined connecting portions, and the ends of said plate having turned flanges for fitting around the corner posts of the car, said flanges having ribs extending around the corner and fashioned to form
 15 compensating portions maintaining equal lengths of profile in all parallel intersecting planes both longitudinally and transversely of the plate.

9. A fashioned metal plate for car ends
 20 of a form which can be developed from a plane sheet without material drawing or stretching of the metal, the body of said plate having the greater portion of its area lying in two spaced parallel planes with intermediate connecting portions, and the ends of said plate being turned to form flanges extending about the corner posts of the car, said flanges being ribbed to correspondingly contract their over-all dimension
 25 to equal that of the body portion of the sheet and to maintain equal lengths of profile, and the portions between the portions lying in said spaced parallel planes and said flanged portion being fashioned to maintain equal lengths of profile in all horizontal
 30 planes.

10. A fashioned metal plate developed
 35 from a plane sheet having portions lying in spaced parallel planes connected by obliquely arranged portions, and a portion lying in a plane transverse to and at the end of the portions in said parallel planes, the latter portion being ribbed and the ribs thereof extending around the corner, said
 40 plate having substantially equal lengths of

profile in all parallel planes intersecting both longitudinally and transversely of the plate.

11. A fashioned metal plate having the greater part of its area disposed in spaced 50 parallel planes with obliquely inclined connecting portions therebetween, and a portion at the end thereof in a plane transverse to all of said first-mentioned portions, the original dimensions of the sheet being uniformly contracted in all portions of the fashioned plate, whereby the marginal portions of the plate maintain their original angular relation.

12. A fashioned metal plate developed 60 from a rectangular plane sheet, the body portion of said plate having the greater part of its area disposed in spaced parallel planes with intermediate connecting portions, and an end portion of the plate being turned to form a flange in a transverse plane, the dimensions of said plate being uniformly contracted to maintain the same rectangular relation in the margins of the plate and equal lengths of profile in all parallel planes of intersection.

13. A fashioned metal plate for car ends of a form which can be developed from a plane sheet without material drawing or stretching of the metal, the body of said 75 plate having spaced planes with intermediate obliquely inclined portions, and the ends of said plate having turned flanges for fitting around the corner posts of the car, said flanges having ribs extending around the 80 corner and fashioned to form compensating portions maintaining equal lengths of profile in all parallel intersecting planes both longitudinally and transversely of the plate, and inserts in the ends of said ribs for closing the same.

In testimony whereof I affix my signature.

FREDERICK M. WHYTE.
